COP HOLDER

Robert V. Olson and Bror A. Johnson, Attleboro, Mass., assignors to Mossberg Pressed Steel Corporation, a corporation of Massachusetts

Application September 1, 1945, Serial No. 614,004

5 Claims. (Cl. 242—121)

1

This invention relates to a cop holder for a braiding machine.

In the use of cop holders such as shown in Patent No. 1,828,337, it has been found, with the increased tensions on yarns which are now being applied by the machines in which cop holders are used, that a stronger resistance to turning of the cop on the holders must be provided for. In the use of resilient arms or ribs, such as shown in the above-mentioned patent, in some instances it has been found that a permanent set occurs in the center of the ribs or arms which interferes with and reduces the holding power on a cop. It has also been found in a cop holder such as shown in the above-mentioned patent that crystallization of the center tube will occur where it extends through the base or head, especially where increased tensions are used and resistances to them are provided for.

One of the objects of this invention is to provide a cop holder which will overcome the above difficulties indicated.

Another object of this invention is to provide a cop holder in which no crystallization will occur of the center tube at its junction with the base or head.

Another object of this invention is to provide a greater stiffness in the resilient arms.

Another object of this invention is to provide resilient arms which will not become permanently set in their center due to use.

Another object of this invention is to provide a cop holder with which stronger yarn tensions may be used and yet one which will withstand such strains as are existant in the use of yarns in a braider at the present time.

With these and other objects in view, the invention consists of certain novel features of construction, as will be more fully described and particularly pointed out in the appended claims.

In the accompanying drawings:

Fig. 1 is an elevation of the improved cop holder;

Fig. 2 is a central sectional view thereof;

Fig. 3 is a bottom plan view;

Fig. 4 is a section on line 4—4 of Fig. 1; and

Fig. 5 is a view similar to Fig. 4 but showing a modified construction.

In proceeding with this invention, we provide two central tubes, one telescoped within the other, and extend both of these tubes through the central opening in the base or head of the cop holder, and secure them in place therein by welding or other suitable means. The outer tube has arms which are arched outwardly and each is

2

generally U-shaped in cross section. In order to stiffen these arms, we place flanges along the edges of the arm which serve to so stiffen these arms that they do not become set in use.

With reference to the drawings, 10 designates generally the base or head of the cop holder, which is provided with a plurality of ratchet teeth 11, cut out and bent into place or cast integral with the plate 12. A collar 13 is provided at the center of the plate 12 surrounding an opening 14 which is formed centrally of the head or base. Two center tubes 15 and 16 are provided, one telescoping the other. These tubes may be either seamless tubes or may be rolled up from sheet stock forming a seam and welded together. Or one tube may be seamless and the other seamed, optionally.

The inner tube 15 is a straight tube which is uniform throughout its length. The outer tube 16 is formed with longitudinally arched arms or ribs bent outwardly therefrom and each rib is U-shaped in cross section as shown at 18 in Fig. 4. The edges of each of these arms or ribs 17 are provided with flanges 19 extending laterally therefrom which serve the purpose of stiffening each of these arms or ribs which, by reason of their length and being bent outwardly, are resilient. It is found that this flange will prevent the ribs from taking an inward set which in many instances becomes permanent where these flanges are absent. The ribs of the outer tube 16 commence at a point 20 spaced from the upper end and terminate at a point 21 spaced from the lower end. The two end portions 22 and 24 from the point of joining of the ribs to the ends of the tube 16 are of band form. The end portion 22 is secured to the end portion of the inner tube 15 by welding, such for instance as spot welding as at 23, while the lower portion 24 of the tube 16 is secured to the lower portion of the tube 15 by welding, such for instance as by spot welding 25. Any welding, brazing or fusing together of the parts, however, is satisfactory, and the spot welding is here shown by way of example only.

Both tubes 15 and 16 extend through the central opening 14 and both are flared over as at 26, or they may be staked over, to lock them in place in the central opening. This locking may occur in any suitable manner, and I also weld or braze the portion which extends through the opening 14 to the collar 13 so that the center tubes will be firmly fixed in place.

A tube constructed as set forth above is found to provide ribs or arms which will not become permanently set in use, and by reason of both cen-

ter tubes extending through the central opening of the base and being fixed thereto, we find that even though greater tension on the yarn is exerted, crystallization of the center tube at the point of its junction with the base or head is avoided.

In some cases instead of having four ribs formed by the outer tube we may have three where the gripping of the cop is to be varied as shown in Fig. 5.

We claim:

1. A cop holder comprising a ratchet base having a central opening therein, a pair of center tubes with one telescoping the other, and both extending through said central opening and in contact at their end portions and secured together.

2. A cop holder as set forth in claim 1 wherein the outer tube has outwardly extending bowed arms to resiliently grip a cop.

3. A cop holder comprising a ratchet base having a central opening therein, a tube in said cen-

tral opening and a second tube telescoping over the first tube and provided with resilient arms in longitudinally arched relation to said center tube and each U-shaped in cross section with a flange 5 along an edge thereof.

4. A cop holder as set forth in claim 3 wherein both edges of the U-shaped cross sections are flanged.

5. A cop holder as set forth in claim 3 wherein 10 both tubes extend through said central opening.
